UNITED STATES PATENT OFFICE.

JAMES PATRICK CAIN, OF SINTON, TEXAS.

FASTENER FOR COTTON-BALE BANDS.

1,278,434.

Specification of Letters Patent. Patented Sept. 10, 1918.

Application filed February 6, 1915. Serial No. 6,501.

To all whom it may concern:

Be it known that I, JAMES P. CAIN, a citizen of the United States, residing at Sinton, in the county of San Patricio and State of Texas, have invented a new and useful Fastener for Cotton-Bale Bands; and I do hereby declare the following to be a full, clear, and exact description of the invention, such as will enable others skilled in the art to 10 which it appertains to make and use the same.

This invention relates to the art of cotton baling, and particularly to a new and useful fastener for the metal bands or straps.

15 Heretofore in baling cotton, it is found that the old form or style of fastener very often becomes broken, especially upon heavy baling, thereby necessitating the bale to be put through the press a second or third time 20 to be rebanded, and moreover in the old method, ten or twelve bands are necessarily used upon heavy bales (which are thoroughly and compactly compressed) to hold the bale properly compressed, and maintain 25 the required density. Moreover, in certain sections of the country, for instance, the State of Texas, a law has been enacted against what are termed "spiders" on bale cotton. In other words in the old method 30 the bands are so applied on the bale, and severed or cut, thereby leaving jagged or sharp portions, which more or less injure the hands, when handling the bale. This law carries a penalty of \$250.00 for each "spider" 35 that may be discovered on a bale, therefore it will be seen under what expense or liabilities cotton is baled.

Therefore, as an object of the present invention it is the aim to overcome the foregoing difficulties and disadvantages, by providing an improved fastener, so constructed that the adjacent ends of the bands may be securely fastened, and leave no spiders or jagged portions on the bale, and at the 45 same time to provide a fastener, which, when used in conjunction with the bands, fewer bands will be required for the baling of cotton.

In practical fields the details of construction may necessitate alterations, falling within the scope of what is claimed.

The invention comprises further features and combination of parts, as hereinafter set forth, shown in the drawings and claimed.

55 In the drawings:—

Figure 1 is a view showing a bale of cot-

ton, and improved fastener as applied to the bands thereof.

Fig. 2 is an enlarged detail perspective view of the fastener showing the hook end 60 of the band about to be connected to the fastener.

Fig. 3 is a detail perspective view of the fastener showing the hook end of the band partially connected to the fastener. 65

Referring more particularly to the drawings, 1 and 2 designate the adjacent end portions of a cotton bale band, and 3 the fastener, which connects the two adjacent ends. This fastener comprises a metallic plate of 70 rectangular shape, which is provided with two elongated openings 4 and 5. The end portion 1 of the band is passed through the opening 4, and then bent as shown at 6, thereby securely fastening the same as 75 shown. This connection is made, and then the band is passed about the bale, as it leaves the press. The other end of the band is then bent to form the U-shaped hook 7. The portion 8 of the plate is deflected as 80 shown, and it will be observed that the bar 9 between the two openings 4 and 5 is severed, to form an open connection as shown at 10 between the openings 4 and 5. In this manner the bar 9 forms two lugs, with which 85 the U-shaped hook portion 7 of the band engages. It will be observed that the openings 4 and 5 are substantially of the same length, however, one end of the opening 4 is constructed V-shaped as shown at 11, there being adjoining shoulders 12 and 13, and between the shoulder 12 and the other end of the opening 4, the bent part of the end 1 of the band engages, thereby preventing lateral play of the band. The fold or bent part 14 95 of the hook 7 of the band engages between the shoulder 13 and the other end of the opening 5 as at 15, to likewise prevent lateral play. One of the lugs 16 of the bar 9 is deflected upwardly out of alignment with 100 the opposite lug, so that as the bale leaves the press, and the band is passed about the same, with the fastener attached to the end 1 of the band, the hook 7 may be disposed on a slight angle and passed between said 105 lug, and then by disposing the hook 7 in a horizontal plane substantially, and releasing it, the edge 19 of the fold of the hook will slide against the inclined edge 20 of the V-shaped end of the opening 4, thereby allowing the hook 7 to engage between the shoulder 13 and the other end of the opening 4,

in the manner shown in Fig. 1. In the drawings the steps employed in fastening the hook 7 are clearly disclosed. It will be seen that when connecting the hook 7 the edge 19 of the fold engages the apex of the V-shaped end of the opening 4, and by slightly pressing said hook 7 in order to maintain this engagement, the hook will remain in such positions, until it is thrown substantially horizontally, and then by releasing said pressure the hook 7 will slide down the incline and make the engagement secure.

The bar 21 of the fastener, and which is adjacent the elongated opening or slot 5 acts to strengthen the entire fastener, not only reinforcing the fastener, thereby preventing the fastener from becoming broken or destructible, but also preventing the band from becoming twisted or displaced, to such an extent that the part 22 will not project laterally which would otherwise cause or form a spider or jagged projection, which would injure the hand. If it were not for the bar 21, the fastener would become distorted to such an extent that the side portions would spread laterally, owing to the tightness of the band, and furthermore if the side portions should become distorted, that is, if the bar 21 was not employed, one end of the band would become detached. However, since the bar 21 is utilized, the side portions of the fastener are prevented from spreading laterally.

The invention having been set forth, what is claimed as new and useful is:—

A bale band fastener, comprising a substantially rectangular plate having a pair of transversely disposed elongated openings arranged in parallelism, one of said openings at one end having a V-shaped portion,

and the opposite edge walls of said opening immediately adjacent said V-shaped portion having directly opposing shoulders, thereby preventing the opposite looped ends of a bale band from riding the inclined edges of said V-shaped portion, whereby interference of one looped end with the other, is prevented when one looped end is caused to engage an inclined edge of said V-shaped portion, the end of the opening opposite said V-shaped opening being rectangular, the other opening being rectangular in contour corresponding in length with the first described opening, said plate having a pair of lugs intermediate said openings, one extending toward the other, and a portion of the other being deflected outwardly from the plane of the plate, whereby one looped end of a bale band may engage therewith and one of the inclined edges of the V-shaped portion in order that said looped end may engage the opposite lug, between the shoulder adjacent the deflected lug and the rectangular end of the opening having the V-shaped portion, the portion of the plate having the rectangular opening from a part adjacent said lugs being deflected or bent toward the bale, thereby permitting the looped end of the bale band which engages said lugs to extend through the rectangular opening, thereby holding the bent portion of the plate into the bale and preventing movement of the fastener plate.

In testimony whereof I have signed my name to this specification in the presence of two subscribing witnesses.

JAMES PATRICK CAIN.
